Specification of Letters Patent. Patented May 2, 1922.

Application filed April 17, 1914. Serial No. 832,628.

(GRANTED UNDER THE PROVISIONS OF THE ACT OF MARCH 3, 1921, 41 STAT. L. 1313.)

To all whom it may concern:

Be it known that I, OTTO EPPENSTEIN, a citizen of the German Empire, residing at Jena, Germany, have invented a new and 5 useful Telemeter System, of which the following is a specification.

The invention relates to a system of telemeters, each of which comprises, for measuring purposes, a setting device and each 10 of which is intended for an observer. According to the invention the said setting device is caused to act on a joint indicating device, so that on the scale of the latter there is indicated automatically a mean value of 15 the values given by the single telemeters. It is probable, that in the said mean value, which has already sometimes been formed by calculation, the incidental errors of the single values and, a considerable number of 20 telemeters coacting, the personal errors of the single observers as well (as the latter errors may also be positive or negative) have compensated one another. In addition to this, the said mean value corresponds, the 25 telemeters being placed at different stations, if only their distance from one another relatively to the distance of the object to be measured be comparatively small, to the distance of a mean station from the object to 30 be measured.

The effect of the setting device on the joint indicating device need not always be the same. When it is a matter of uniting the 35 readings of telemeters having a comparatively small distance apart to one mean value, their setting devices will with advantage be mechanically interconnected for the purpose of acting on the joint indicating device. When there are only two telemeters 40 and these two telemeters are adjacent to one another, it is of especial advantage to let a common carrier serve for their reception, which carrier may be formed as a common casing for the two telemeters. The said 45 carrier makes it possible on the one hand, to make the mechanical connection of the setting devices into a permanent one, so that a repeated adjustment of the joint indicating device is avoided, and it permits on the other 50 hand, that simultaneously for both telemeters the setting in the height-direction may be left to one of the observers, while the setting in the horizontal plane is left to the

other one. When in such an arrangement the setting devices of the two telemeters each 55 comprise a system of refracting prisms, they may be connected together by means of differential gearing, that member of the gearing, which is moved by the two setting devices (the planet pinion), serving for actuating the joint indicating device. According as the said indicating device is to perform a rotary motion or a displacement, those wheels of the differential gearing, which are rotatable only about their own 60 axes, (the crown wheels), are given a radius of finite or of infinite length. In the latter case they take the form of racks, along which the planet wheel of the gearing is 65 displaceable. When it is desired not to 70 adopt differential gearing, the two setting devices may, for example, be connected together in such a manner that one of them moves the scale and the other the index of the joint indicating device. 75

In order to unite the readings of adjacent telemeters, for the reception of which a common carrier is again employed, to a mean value, it is also possible to connect an optical system with this carrier, by means of 80 which an image of one of the two members of the joint indicating device of the telemeters (viz. the index-mark or the scale) is formed on the other one or on an image of the same, the setting devices of the telemeters influencing the position of the image of the one member relatively to the other, in so far as an image of this other member is formed as well, relatively to the image of this latter member. 85 90

When from the readings of any number of telemeters having any distance between them a mean value is to be formed, the setting device of each telemeter may be with advantage coupled to the shiftable part of the transmitter of an alternating current long distance indicator and all these transmitters allowed to act on a single receiver, which is connected to an indicating device, the shiftable part of the receiver being put in parallel with the shiftable parts of the transmitters and its non-shiftable part and the non-shiftable part of each transmitter being connected up with an alternating current network in such a manner that in the non-shiftable parts a rotating field is created. 95 100 105

When the system consists of two adjacent uniocular coincidence telemeters, the base-lines of which are of about the same length and the setting devices of which act on a joint indicating device, and if these telemeters can be connected up relatively to each other in such a manner that their base-lines become parallel to one another and that each of the two ray pencil systems emerging from the first telemeter is presented to the corresponding entrance opening of the second telemeter (in telemeters, the base-lines of which have different lengths, or in telemeters, the entrance openings of which are turned away from each other, for instance by means of suitable reflecting systems), so that the image of an object, which lies or an image of which is formed in the focal plane of the objectives of the first telemeter, is formed in the focal plane of the objectives of the second telemeter, the approximate arithmetical mean value of the distances of the object to be measured can be given on the joint indicating device by the two telemeters, even without either of the two telemeters being correctly adjusted. For, if the ray pencil system emerging from the first telemeter, as may be seen from German patent specification 251,041 for a special case, be each presented to the corresponding entrance opening of the second telemeter in such a manner that the angle formed by each emerging ray pencil system with the base-line of the particular telemeter is equal to the supplement of the angle formed by the ray pencil system belonging to it entering the other telemeter with the base-line of the latter telemeter (which is of itself the case in telemeters, the base-lines of which are of equal length and the entrance openings of which face each other), and when the state of adjustment of the first telemeter deviates from the correct adjustment and when the setting device of this telemeter is set in such a manner that the corresponding indicating device indicates the value infinitely, and thereupon the setting of the indicating device of the second telemeter, coincidence having been obtained for the said object (which lies or of which an image is formed in the focal plane of the objectives of the first telemeter) is altered in such a manner that the said indicating device likewise indicates the value infinity, the two parallax angles belonging to that object, for which the value infinitely is given on the two indicating devices, differ from zero and are equally great, they have, however, opposite signs. When the joint indicating device is likewise set to the value infinity, its scale having to be divided in such a manner that, on setting the indicating devices of the two telemeters to the same indication, the same value is given also on it, and when the movements of the said two in-

dicating devices are transmitted to the joint indicating device in such a manner that the latter device is given the arithmetical mean of these movements, the said arithmetical mean corresponds to an angle, which equals the arithmetical mean of the said two parallax angles. This, however, is the angle, that appertains to the object in question. When the two telemeters, the above described settings having been effected, are set for any given object, the true value of the distance of the said object will not be reached by the indication of one of the instruments and will be exceeded by that of the other one, whereas the indication of the joint indicating device corresponds approximately to the said true value. This may be proved by a similar train of thought also for binocular telemeters with setting means, such as are known through the German patent specification 255,955.

When the objective prisms of the telemeters are located in front of the objectives, the objective prisms of one of the telemeters will be, in order that the above described settings of the two instruments may be effected, disposed with advantage in such a manner that they can be changed from their position, which corresponds to the measuring condition of the telemeter, into a position, in which they face the objective prisms of the second telemeter. When the base-lines of the two telemeters are parallel to one another, a joint carrier may (in the case of adjacent telemeters) be with advantage employed for their reception, which carrier may be formed as a joint casing, and, in the case of one of the telemeters, on the one hand the objective prisms are disposed in such a manner that, on being rotated in the plane of triangulation by 90° , they can be turned to face the entrance surfaces of the objective prisms of the other telemeter with what were so far their emergence surface, and on the other hand the objectives and the separating prism system are disposed in such a manner that they can be jointly rotated through 180° about an axis, which is parallel to the base-lines, the said axis of rotation having such a position that the objective prisms each again come to lie in the path of rays of the corresponding objective. If, however, the setting device does not take part in the said rotation through 180° , care must be taken, that any errors of adjustment arising thereby are compensated.

In the annexed drawing: Fig. 1 is a diagrammatic representation of the telemeter system according to the invention. Figs. 2 to 4 show a constructional example of the new telemeter system, Fig. 2 being a vertical section through the joint casing, Fig. 3 a plan view and Fig. 4 a cross-section on line 4-4 of Fig. 2. Figs. 5 to 8 show a second constructional example of the new telemeter

system, Fig. 5 being a vertical section through the joint casing, Fig. 6 a vertical section on line 6—6 of Fig. 7, Fig. 7 a plan view partly in section and Fig. 8 a cross-section on line 8—8 of Fig. 7. Figs. 9 to 11 show a third constructional example of the new telemeter system, comprising 3 telemeters, Fig. 9 being a plan view of one of the three telemeters, Fig. 10 a diagrammatic representation of the whole telemeter system to a larger scale, only that part of each telemeter being shown, which contains the setting device, and Fig. 11 a side elevation of the said part. Figs. 12 to 14 show a fourth constructional example of the new telemeter system, Fig. 12 being an elevation partly in section, Fig. 13 a horizontal section through the joint casing on line 13—13 of Fig. 12, containing the common sighting plane of the telemeters, and Fig. 14 a cross-section on line 14—14 of Fig. 13, containing the axes of inspection.

In Fig. 1 the system consists of two unioocular telemeters of equal dimensions, 25 having a common base-line outside the instrument. Each of the two telemeters comprises an objective 1, a twice reflecting prism 2, which deflects the entering rays by 90°, an isosceles right-angled ridge-prism 3, a Ramsden ocular 4 and a Rochon prism 5, which is displaceable in the direction of the optical axis, the telemeters having such a relative position, that the direction of entrance of the rays is the same for both of them, while corresponding displacements of the Rochon prisms are parallelly and oppositely directed. One of the Rochon prisms is connected with the scale 6 and the other with the index 7 of an indicating device, 40 which is common to the two telemeters. The scale 6 is parallel to the direction of displacement of the prisms and is divided in such a manner that the index 7 gives on it the arithmetical mean value of the displacements of the Rochon prisms, which value corresponds approximately to the arithmetical mean value of the distances measured by the separate telemeters.

In the constructional example, Figs. 2 to 50 4, the system consists of two unioocular coincidence telemeters, which are disposed one above the other in a joint casing and the base-lines of which are parallel to one another and of equal length and each belong 55 to the instrument, one image in the case of each telemeter being inverted in the direction perpendicular to the base-line. The setting devices of the two telemeters comprise each a displaceable refracting prism 50 and are connected together by differential gearing, the crown wheels of which are represented by racks. The optical systems of 60 the two telemeters are disposed in the joint casing 8 and comprise each two objectives 9, 65 two twice reflecting prisms 10, which are

located in front of the said objectives, a separating prism system 11 and an astronomical ocular 12. While the entrance surfaces of the prisms 10 of both telemeters face one and the same side of the casing, 70 the oculars 12 are located at different sides, so that their directions of inspection are opposite to one another. The optical part of each of the two measuring devices is formed by a refracting prism 13, which is displaceable in the horizontal direction and is disposed between the separating prism system and the objective lying in the drawing to the right of each telemeter. Each of these prisms 13 is connected with a scale 14, which 75 can be observed at the inspection side of the telemeter belonging to it through a window 15 in the casing, which bears the corresponding index 16. The two prisms 13 are so chosen and disposed that, in order to pass 80 from the setting of the two measuring devices for a first common object to the setting for a second common object, the two prisms must be displaced by equal amounts and in 85 the same directions. For being set each 90 prism carrier 17 is fitted with a rack 18, with which a pinion 19 engages, which can be actuated by means of a milled head 20. Two further racks 21, which each belong to one of the prism carriers 17 and are parallel 95 to the direction of displacement of the prisms 13, engage with their teeth facing each other with a toothed wheel 22. This toothed wheel is rotatably mounted on an arbor 23, which is guided by means of two 100 slides 24 in the casing 8 in the direction of displacement of the prisms 13. Each of the slides is fitted with a scale 25, which has the same divisions as the scales 14 of the setting devices, and can be observed through a window 26 in the casing 8, which bears the corresponding index 27. By means of these indicating devices 25, 27 the arithmetical mean value of the prism displacements is indicated on each of the two inspection sides 110 of the telemeter, which value approximately corresponds to the arithmetical mean value of the distances measured by the separate telemeters.

In the constructional example, Figs. 5 to 115 8, the system again consists of two unioocular coincidence telemeters disposed one above the other in a joint casing, the base-lines of which telemeters are parallel to one another and of equal length and each 120 belong to the instrument, one of the images in each telemeter being inverted in the direction perpendicular to the base-line. Each telemeter comprises two objectives 28, two twice reflecting prisms 29, which are located in front of these objectives, a separating prism system 30 and an astronomical ocular 31, a joint casing 32 serving for the reception of the said two optical systems. While the entrance surfaces of the prisms 29 130

of both telemeters face one and the same side of the casing, the oculars 31 lie at different sides, so that their directions of inspection are opposite to one another. The optical part of each of the two measuring devices comprises two equal refracting prisms 33 and 34, which are rotatable in opposite directions, but through the same angle, and lie between the objective, which lies to the right in the drawing, and the prism located in front of the same of each telemeter. The movement of these refracting prisms is effected from the arbor of the measuring drum 35 by means of bevel wheels 36, 37 and 38. The two measuring devices are chosen and disposed in such a manner that, in order to pass from the setting for a first common object to the setting for a second common object, two prisms, which correspond to one another and each belong to one of the two measuring devices, for instance the two prisms 33, each of which is adjacent to the objective prism belonging to it, are to be rotated by equal amounts, but in opposite directions. On that side of the joint casing 32 of the two telemeters, which is remote from the object to be measured, there is fixed an optical system, which comprises an objective 39, a collective lens 40, a lens of reversion 41 and a Ramsden ocular 42, three isosceles right-angled prisms 43 being introduced into the path of the rays for thrice deflecting the rays, each time through 90° . The optical system serves for forming an image of an index 44 disposed in front of its objective 39 on a scale 45 lying in the focal plane of the ocular, which scale together with the index represents the indicating device common to the two telemeters. The influence of the setting devices on the said indicating device is effected in each case by means of a direct vision (Amici) prism 46, the mounting 47 of one of these prisms being rotatably journaled between the objective 39 and the collective lens 40 and that of the other prism between the collective lens 40 and the lens of reversion 41 in such a manner that the axis of rotation of each prism is represented by the common axis of the entering and emerging ray pencil and coincides with the axis of the optical system. For transmitting the setting movements the two refracting prisms 33, which belong each to one of the two setting devices and are adjacent each to the right-hand corresponding objective prism, are each fitted with toothings 48, with which meshes a toothed wheel 49 of one and of the other prism mounting 47 respectively, which toothed wheels have the same number of teeth as the said toothings. The rotation of such a direct vision prism 46 will cause, as is well known, the image of the index 44 to rotate relatively to the scale 45 through an angle, which is twice as great as the angle of rotation of the prism itself. Two

such direct vision prisms, which, seen in the direction of the light, are rotated in the same sense, therefore act on the image of the index in such a manner that it is rotated through an angle, which is equal to twice the sum of the angles of rotation of the said prisms. As it has been assumed, that the number of teeth of the toothings 48 and 49 is the same, so that the refracting prism 33 of one of the two setting devices and the corresponding direct vision prism 46 can rotate only through equal angles, it follows, that the image of the index is subject to a rotation, which is equal to an angle of twice the sum of the angles of rotation of the said refracting prisms 33. Now, in order that the arithmetical mean value of these angles of rotation will be indicated on the scale, which value approximately corresponds to the arithmetical mean value of the values measured by the separate telemeters, this scale must be divided in such a manner that its intervals, measured in angular units, are four times as great, as corresponding angles of rotation of the refracting prisms 33. If the length of scale be restricted to one complete circle, it follows, as the toothings 48 and 49 have equal numbers of teeth, that only an angle of rotation of the refracting prisms of 90° is permissible.

In the next constructional example, Figs. 9 to 11, the system consists of three unocular coincidence telemeters having the base-line within the instrument, one of the images in each telemeter being inverted in the direction perpendicular to the base-line. The optical system of each of the three telemeters consist of two objectives 50, two twice reflecting prisms 51 located in front of these objectives, a separating prism system 52 and an astronomical ocular 53. The optical part of each setting device is formed by a refracting prism 54, which is displaceable in the direction of the base-line, is disposed between the separating prism system 52 and the right-hand objective of each telemeter and the movement of which is to be supposed as being effected from the arbor of a toothed wheel 55 by means of rack and pinion drive. In order to be able to obtain the arithmetical mean value from the displacements of the refracting prisms, which mean value corresponds—for proportionately small relative distances of the three telemeters as compared with the distance of the object to be measured—approximately to the arithmetical mean value of the distances of the separate telemeters from the object to be measured, each telemeter is fitted with the transmitter of an alternating current long distance indicator, which is actuated by two currents coming from a generator 56, which are 90° out of phase. The lines of these currents are marked 57 and 58 and the equalizing line 59. The sta-

tionary part of each transmitter consists of two pairs of coils 61 and 62, which are wound on an iron ring 60 and which are so located that the connecting lines of their single coils form two diameters of the ring, which are perpendicular to one another, while the movably disposed part comprises only one pair of coils 63, the single coils of which also form a diameter of the said ring. The pair of coils 63 is fixed to a toothed wheel 64, which meshes with the toothed wheel 55 of the setting device of the corresponding telemeter and can be actuated by means of a milled head 65, the toothed wheel 64 having such a number of teeth that one revolution of this wheel corresponds to the total displacement of the refracting prism 54. The three transmitters of the long distance indicator are served by a single receiver, the stationary part of which consists of two crossed coils 66 and 67, while its movable part comprises a moving coil 68, which is fitted with an index 70 belonging to a scale 69. Now the transmitters and the receiver are connected up in such a manner that, on the one hand, the coils 61 and the coil 66 are connected to the circuits 57 and 59 and the coils 62 and the coil 67 to the circuits 58 and 59, so that in the stationary parts of the transmitters and in that of the receiver a rotating field of the same phase is created, and that, on the other hand, the coils 63 and the coil 68 are connected in parallel by means of the lines 71 and 72. The effect of this is, that the currents induced, on setting the telemeters, in the pairs of coils 63, in consequence of a rotation of each of the pairs of movable coils 63 of the transmitters relatively to the corresponding stationary coil system 61, 62, act on the moving coil 68 of the receiver in such a manner that the index 70 indicates on the scale 69 the mean value of the said rotations, which value approximately corresponds to the mean value of the distances of the single telemeters from the object to be measured.

In the last constructional example of the invention, Figs. 12 to 14, the system consists of two unocular coincidence telemeters, which are disposed one behind the other in a joint casing and the base-lines of which are parallel to one another, are of different length and belong each to the instrument, one of the images in each telemeter being inverted in the direction perpendicular to the base-line. For acting upon the joint indicating device, the two setting devices are again connected together by means of differential gearing. In the joint casing 73 there are disposed two inner tubes, one of which, 74, is fixed to the casing, while the other, 75, is journaled, so as to be rotatable about its axis, and can be rotated, through the turning of a milled head 76

through 360°, by means of a pair of bevel wheels 77, 78 through 180°. The extreme positions of the inner tube are indicated on the said milled head by an index 79, which is fitted on the casing. Each inner tube 75 contains the two objectives 80 and the separating prism system 81 of one of the two telemeters, while the two astronomical oculars 82 belonging each to one of the telemeters are each fixed opposite an opening 83 of the particular inner tube to the outside of the casing in such a manner that their axes of inspection are directed oppositely to each other. The objective prisms 84, which belong to the rear telemeter (with the immovable inner tube 74), are fixed in the casing, whereas the objective prisms 85 belonging to the front telemeter can be rotated by means of a milled head 86 through 90° in the common sighting plane 85 of the telemeters. In one of their extreme positions these objective prisms 85 face, as do also those of the second telemeter, the object to be measured and determine a baseline, which is greater than that of the said second telemeter, while in their other extreme position they face with what were so far their emergence surfaces 87 the entrance surfaces 88 of the objective prisms of the second telemeter. The said two extreme positions are indicated on the milled head 86 by means of an index 89 fitted to the casing. The optical part of each of the two measuring devices again comprises two equal refracting prisms 90 and 91, which are rotatable in opposite directions, but through equal angles and which lie between the right-hand objective and the prism located in front of it of each telemeter, and the movement of these refracting prisms is effected from the arbor of the setting drum 92, which forms with the index 93 fitted on the casing the indicating device of the particular telemeter, by means of bevel wheels 94, 95 and 96. The two measuring devices are chosen and disposed in such a manner that, for passing from the setting for a first common object to the setting for a second common object, two refracting prisms, which correspond to one another and belong each to one of the two measuring devices, e. g. the two prisms 90, each of which is adjacent to the objective prism belonging to it, are to be rotated by equal amounts, but in opposite directions. These two prisms 90 are each connected with one of the two crown wheels 97 of a differential gearing, one of them directly and the other by means of a pair of gear wheels 98, each of which has the same number of teeth. The planet pinion 125 99 of the said differential gearing is rotatably journaled on an arbor 100, which is fixed to a box 101, and this box bears on its outer periphery a scale 102, which may be observed through a window 103 in the cas- 130

ing and forms together with an index 104 on the said window the indicating device common to the two telemeters. This scale is so divided that, on the indicating devices 5 of the two telemeters being set to corresponding indications, the same value is indicated on it. In order to be able to present to the separating prism system of the front telemeter, after its inner tube has been rotated 10 by 180° out of the position corresponding to the measuring position, the image of an object lying in front of the telemeter, an optical system is provided, consisting of an objective 105 and of two 15 isosceles right-angled reflecting prisms 106 and 107.

The telemeter system is adjusted in the following manner: The inner tube 75 of the front telemeter is brought by means of the 20 milled head 76 into a position, in which its opening 83 faces the reflecting prism 107, and the two objective prisms 85 are each moved by means of the milled head 86 into that extreme position, in which what was so 25 far the emergence surface 87 faces the entrance surface 88 of the corresponding objective prism 84 of the rear telemeter. Thereupon the setting drum 92 of the front telemeter is rotated, until its pointer 93 indicates the value infinity, at which indication 30 the refracting prisms 90 and 91, deviating from the usual disposition, occupy that position, in which their refractive effect is equal to that of a plano-parallel glass plate. 35 An image of a ray pencil system coming from an object lying in front of the objective 105 of the optical system is formed by the said objective in the separating prism system 81 of the front telemeter and is there 40 split up into two part pencil systems, each of which is transmitted to one of the two corresponding objectives 80, so that by each objective an image of the said object is presented to one of the objectives of the rear telemeter. Coincidence is now brought about 45 with the aid of the setting drum 92 of the said rear telemeter for the said object, and the corresponding index 93 is set so as to indicate the value infinity, whereupon the inner tube 75 and the objective prisms 85 of the front telemeter are moved into their 50 other extreme positions, so that the telemeter assumes its operative position. If finally the index 104 of the joint indicating device be set so as to indicate the value infinity on the corresponding scale 102, on 55 setting the telemeters for any desired object, a value is indicated on this indicating device, which approximately corresponds to the arithmetical means of the distances of the said object from the telemeters, it being immaterial, whether each of the telemeters was correctly adjusted or not. In the case 60 of larger angles of rotation of the refracting prisms 90 and 91, instead of making the in-

dex 93 of the rear telemeter adaptable, a glass wedge may be disposed in front of one of the objectives of this telemeter, which, for bringing about coincidence for the said object, on the indicating device being set for 70 the value infinity, is to be rotated in a plane, which is perpendicular to the optical axis. In this case the index 104 of the joint indicating device need also not be adaptable.

I claim:

1. In a telemeter system a plurality of telemeters, a setting device for measuring purposes contained in each telemeter and an indicating device common to the said telemeters and consisting of a scale and an index, at least one of which two parts being movable, and means for coupling the said setting devices and the said indicating device and for causing a relative movement of the two parts of the said indicating device, which movement corresponds to a mean value of the values given by the single telemeters.

2. In a telemeter system a plurality of telemeters, a setting device for measuring 90 purposes contained in each telemeter and an indicating device common to the said telemeters and consisting of a scale and an index, at least one of which two parts being movable, and mechanical means for coupling the said setting devices and the said indicating device and for causing a relative movement of the two parts of the said indicating device, which movement corresponds to a mean value of the values given 100 by the single telemeters.

3. In a telemeter system two telemeters, a common carrier for the reception of the said two telemeters, a setting device for measuring purposes in each telemeter, each 105 of which devices comprises a system of refracting prisms, an indicating device common to the said telemeters and consisting of a scale and an index, one of which two parts being movable, and differential gearing, each of the said setting devices being connected with one of the crown wheels of the said gearing and the movable part of the said indicating device being connected with the planet wheel of the said gearing.

4. In a telemeter system two adjacent self contained base telemeters with base lines of approximately the same length, the objective prisms of each telemeter being located in front of the objectives, a setting device for measuring purposes contained in each telemeter, an indicating device common to the two telemeters and consisting of a scale and an index, at least one of which two parts being movable, means for turning the objective prisms of one telemeter to face those of the other telemeter and means for coupling the said setting devices and the said indicating device and for causing a relative movement of the two parts of the 125 130

said indicating device, which movement corresponds to a mean value of the values given by the single telemeters.

5. In a telemeter system two self contained base telemeters with parallel base lines of approximately the same length, a separating prism system in each telemeter, a common carrier for the reception of the two telemeters, the objective prisms of each 10 telemeter being located in front of the objectives, a setting device for measuring purposes contained in each telemeter, an indicating device common to the two telemeters and consisting of a scale and an index, at 15 least one of which two parts being movable, means for rotating the objective prisms of one of the telemeters in the sighting plane

through 90° to face with what were so far their emergence surfaces the entrance surfaces of the objective prisms of the other 20 telemeter, means for rotating the objectives and the separating prism system of the former telemeter through 180° about an axis, which is parallel to the base lines, and means for coupling the said setting devices 25 and the said indicating device and for causing a relative movement of the two parts of the said indicating device, which movement corresponds to a mean value of the values given by the single telemeters.

OTTO EPPENSTEIN.
